motive Fibres, Inc., Detroit, Mich., a corpora-
tion of Delaware

Application November 6, 1939, Serial No. 303,164

3 Claims.

(Cl. 18—6)

The present invention relates to the decoration of fabric and more particularly to a new and improved apparatus for decorating fabric.

It has in the past been suggested that fabric be decorated by applying a thin ply of rubber, either expansible or substantially nonexpansible, to the rear surface thereof, after which pressure be applied to the forward face of the fabric in predetermined areas, displacing rubber from beneath the areas of pressure into upstanding beads, ridges and the like intermediate said areas of pressure.

For this purpose it has in the past been suggested to employ a continuous rotary machine in which a drum of relatively large diameter is heated. The elements going to make up the completed decorated fabric are advanced over the heated drum, preferably with the rubber adjacent the drum. Pressure is then applied to the dress or front face of the fabric by means of a designed band suitably tensioned.

According to the present invention we have devised novel apparatus for producing decorated fabric of the type referred to, and the apparatus has new and improved functions.

Briefly described, the present apparatus comprises a horizontally disposed table support. Beneath the upper plane of the table is a roll of rubber, preferably an uncured blowing rubber stock, adapted when heated to swell and vulcanize. An endless belt is supported between two pulleys located beneath the upper surface of the table. The upper surfaces of the pulleys are substantially tangent to the surface of the table, with the result that the upper portion of the belt is adapted to advance substantially in the plane of the table. Beneath the said upper portion of the belt and in heat transferring contact therewith, we provide an elongated heating unit which is adapted to transfer heat through the belt to a material engaging with the upper surface of the belt.

A second pair of pulleys disposed generally above the plane of the table is provided, and an endless designed belt is carried thereby. The lower portion of the designed belt between the last mentioned pulleys is directly above the upper portion of the first mentioned belt and is normally in contact therewith. Pressure means are provided, pressing the lower portion of the upper belt into firm contact with the upper portion of the lower belt. Extending across the table and at each side of the just described apparatus are a plurality of feed belts adapted to advance fabric thereover.

Rubber from the roll previously referred to is advanced over the upper portion of the lower belt, and fabric is advanced overlying the rubber. By means of the just described apparatus, pressure and heat are applied through the medium of the two belts just referred to, and the rubber is displaced and caused to form upwardly into a predetermined design. At the same time, due to the application of heat, the rubber vulcanizes so that it resiliently retains its displaced form, and further is permanently attached to the fabric.

It is within the contemplation of the present invention that the elongated heating element be provided with a plurality of independent heating units, each of which is separately controllable so that the temperature along the heating unit may be graduated as desired. It is further contemplated that the means for applying pressure to the lower portion of the upper belt may take the form of individual relatively movable pressure shoes, each provided with independently adjustable resilient means for imparting a predetermined pressure thereto. By this arrangement it is possible to predetermine the temperature and/or pressure applied to the rubber and fabric at various points along its advance.

With the foregoing brief description in mind, it is accordingly an object of the present invention to provide a decorating apparatus characterized by the provision of means for horizontally advancing rubber and fabric, for applying heat thereto, and for applying pressure to predetermined areas on the face of the fabric.

It is a further object of the present invention to provide apparatus of the character described, characterized by means for applying variable temperatures thereto.

It is a further object of the present invention to provide an apparatus of the character described, and means for applying variable predetermined pressures to the material.

It is a further object of the invention to provide a pair of endless belts having contacting portions advancing in unison between an elongated heating unit and means for compressing said portions of said belts against the heating unit.

Other objects of the invention will be apparent as the description proceeds, and when taken in conjunction with the accompanying drawings, wherein:

Figure 1 is a side elevation of our improved apparatus;

Figure 2 is a plan view of the apparatus shown

in Figure 1 with the pressure applying structure removed to expose the parts;

Figure 3 is a section on the line 3—3, Figure 1;

Figure 4 is a fragmentary perspective partly in section showing the product of our improved apparatus;

Figure 5 is a fragmentary section showing a modified form of the pressure applying element;

Figure 6 is a fragmentary sectional view showing yet another modified form of pressure applying apparatus.

Figure 7 is a diagrammatic side elevation of a somewhat modified construction;

Figure 8 is a fragmentary bottom plane view illustrating the relationship between the design band and the control band;

Figure 9 is a fragmentary side view illustrating a modified form of design band;

Figure 10 is a section on the line 10—10 of Figure 9; and

Figure 11 is a fragmentary plan view of a portion of the design band illustrated in Figure 10.

Referring first to Figures 1 and 2, the apparatus comprises a table 10 supported by suitable legs 11. A pair of lower pulleys 12 secured to brackets 13 carried by the frame of the apparatus are supported with their upper surfaces substantially tangent to the upper surface of the table 10. A metal belt 14 is carried by the pulleys 12, the upper portion of said belt being indicated at 14' in Figure 1.

Carried by the table 10 is a heating element 15 herein shown as a channel member of U-shaped cross section. The heating unit 15 extends completely from end to end of the table proper. Within the heating unit 15 are a plurality of heating elements indicated generally at 16. As previously stated, the individual heating elements 16 may be separately controllable or adjustable so that the temperature may be graduated as desired along the path of travel.

The heating elements which are employed may be of any type, such for example as electrical resistance elements or the like. In some cases it will be desirable to supply heat by means of steam, or other heating fluids. We have illustrated electrical heating elements as perhaps the simplest form.

In Figure 3 we have indicated insulating material 17 intermediate the heating elements and the channel shaped heating unit 15. Overlying the heating element 16 and enclosing the same is an enclosing member 18 which is of inverted channel shape and which presents a smooth upper surface for a purpose subsequently to be described. As best seen in Figure 3, the upper portion 14' of the metal band 14 is adapted to contact with the upper smooth surface of the member 18.

An upper frame generally indicated at 20 is carried by the table, and in turn supports a pair of pulleys 21 carried by suitable brackets 22. Pulleys 21 have extending therebetween a design band 23, a portion of which is clearly shown in Figure 2. The upper frame 20 includes a longitudinally extending beam 24, and also supports for vertical movement a pressure bar 25. Secured to the beam 24 are a plurality of brackets 26 having slidably retained therein pins 27. Pins 27 project from the lower end of the brackets 26 and engage the upper surface of the pressure bar 25. Received between the lower portion of the brackets 26 and the upper surface of the pressure bar 25 are pressure springs 28 which are retained in position by the lower projecting portion of the

pins 27. Preferably means are provided for adjusting the tension of the springs 28. These means may take the form of a conventional threaded abutment 29 having threaded engagement, for example with the brackets 26 as indicated generally in Figure 3. By this means the pressure applied to the composite material may be controlled as desired, and may be increasing or decreasing from end to end as occasion demands.

In Figure 3 we have illustrated the brackets 26 as secured to a cross member 30 provided with elongated slots 31 so that the brackets 26 may be adjusted transversely of the table to position the pressure means directly over the forming member.

A feed table 32 is positioned immediately in front of the table 10 so that the fabric indicated generally at 33 may be placed thereon and advanced between the rollers 12 and 21. A suitable bracket 34 is provided for supporting a roll of uncured rubberous material 35.

A discharge table 40 is positioned at the discharge end of the table 10 to receive the completed material thereon. A resilient stripper blade 41 is carried by the table and is adapted to contact the lower roll 12 for insuring separation between the leading edge of the decorated material and the roll.

The loading table 32 and the discharge table 40 are both provided with a plurality of feed belts, those on the loading table 32 being indicated at 36 and those on the discharge table being indicated at 42.

Means are provided for driving the various elements of the apparatus, and comprise a motor 50 carried by a cross piece 51 on the frame. The motor 50 is adapted to rotate a sprocket 52 through a suitable speed changing device indicated generally at 53.

A second sprocket 54 is keyed or otherwise secured to a shaft 55 which carries the discharge pulley 12. A chain 56 interconnects sprockets 52 and 54 and cause a rotation of the shaft 55. Preferably a shaft 57 of the upper pulley 21 is provided with a sprocket (not shown) and the two shafts 57 and 55 are driven in timed relation by a chain driving member.

The rates of rotation of the pulleys 12 and 21 are such that the peripheral surface thereof has the same linear rate of advance. By reason of this, the upper portion of the lower belt and the lower portion of the upper belt move together without relative slippage over the heating unit 15.

While we have shown the pulleys 12 and 21 at the right-hand edge of Figure 1 as driven solely by the belts previously referred to, it will be appreciated that a positive chain drive from the shafts 55 and 57 may be substituted if desired.

Referring now to Figure 5 we have illustrated a somewhat modified form of pressure bar 25. In this figure the pressure member 25a is shown as of inverted channel shape having depending flanges 25b. A plurality of closely spaced rolls 25c are provided within the channel and extend a short distance below the flanges 25b. Rolls 25c are provided with pins 25d which mount the rollers for rotation within the channel member. As will be evident, contact between the pressure member 25a and the forming band 23 is in this instance by means of rollers, thus reducing friction and preventing excess wear of the forming members. It will be appreciated that if desired the forming bands 23 may be substantially tensioned so that while the pressure is applied there-

to at separated points by means of the rolls 25, substantially uniform pressure may be exerted by the forming band 23 against the exposed or front surface of the fabric being decorated.

Referring now to Figure 6, we have illustrated a somewhat different modification of pressure means. In this instance the pressure means take the form of individual blocks 60, each provided at its upper surface with a recess 61 for the reception of pins 27, as shown in Figure 3. Pins 27 serve as centering means for the compressing springs 28, which as previously described are preferably independently adjustable. It will be apparent that the pins 27 retain the blocks 60 against displacement in a horizontal plane. Inasmuch as pins 27 may be vertically movable, it is apparent that the blocks 60 are independently vertically movable in like manner. If preferred, the pins 27 may be fixed against vertical movement, in which case the recess 61 in the upper surface of the blocks 60 may be deeper so as to provide for relatively vertical movement between the blocks 60 and the pins 27, as suggested at the left of Figure 6. In this embodiment preferably a rigid abutment is provided against which the block 60 adjacent the discharge end of the machine may rest. By this construction, as will be readily apparent, it is possible to vary the pressure applied to the forming band 23 at different points throughout its travel relative to the heating element 15.

It is desirable to provide this means for varying the temperature and pressure applied to the composite material throughout its travel so that the conditions of temperature and pressure may be coordinated with the particular properties of the uncured rubber stock employed. Thus, in some instances, it may be desirable to apply an initially low pressure and temperature to endure during expansion and molding of the rubber material. After the rubber has been molded to the desired shape, increased temperature and pressure may be applied to perform the final vulcanizing operation.

Referring now particularly to Figure 4, we have illustrated a fragmentary perspective of a portion of a fabric decorated according to the present method. In Figure 4 the fabric is indicated at 70 and may be mohair, linen, artificial leather, or in fact substantially any fabric. We have indicated the rubber at 71, and at 72 we have indicated a backing sheet of reinforcing material such for example as paper or sheeting. When pressure was applied to the upper surface of the fabric 70 throughout areas overlying the rubber 71, the rubber was displaced from beneath these areas into upstanding beads 73. At points where no pressure was applied this upward displacement of the rubber at 73 caused a corresponding movement of the fabric into the upstanding beads 74. Displacement of the rubber into the upstanding beads 73 was permitted by initial slack in the fabric 70 or by a stretching of the fabric 70, or both. The application of heat and pressure as above described caused the rubber 71 to become cured, with the result that the completed article illustrated in Figure 4 has the decorative beads 74, permanently retained therein.

It will be appreciated that the rubber 71 is applied in a very thin strip and that substantially all of the rubber is displaced into the upstanding beads 73. The result of this is that the fabric as a whole does not have its flexibility substantially lessened. At the same time, sufficient rubber remains between the fabric 70 and 75

reinforcing material 72 at points removed from the bead 73 for insuring a permanent vulcanized bond therebetween. The reinforcing material 72 therefore permits substantial tension of the cloth 70 in subsequent use without adversely affecting the beads 74.

In some instances it is desirable to provide apparatus for placing a specific design in a certain relationship on a piece of cloth. Thus for example it may be desired to place a design symmetrically on an individual cover fabric. In Figures 7 and 8 we have illustrated apparatus for this purpose.

It will be understood that these figures are merely diagrammatic and illustrate modifications which may be added to the complete apparatus well illustrated in Figures 1 and 2. In these figures we have indicated a heated table 100 over which the fabric and rubber combination is to be advanced. A heat conducting belt 101 is positioned on feed rollers 102, 103 in such relationship that the upper reach of this belt contacts the upper surface of the heated table 100. A pair of upper rollers 104, 105 carry the design band indicated at 106, and in addition a control band 107 is provided, having upstanding control portions 108 carried thereby. A feed conveyor 110 is located at the entrance side of the apparatus in combination with a suitable supporting table (not shown). The conveyor 110 is mounted between feed rollers 111 and 112. The arrangement is such that a fabric when placed on the conveyor 110 is advanced between the rolls 103, 105 over the heated table 100 in contact with the heated band 101, and design band 106, all substantially as previously described.

In the present embodiment, however, means are provided for causing intermittent actuation of the feed conveyor 110. We have indicated a motor 113 connected by suitable drive means 114 to feed roll 103, and we have indicated at 115 drive means interconnecting the roll 103 and the roll 112 of the feed conveyor 110. The motor 113 is adapted to be energized constantly, with the result that the heating band 101, and the design band 106, and the control band 107 are constantly in motion. A clutch is provided for the roll 112, and a clutch actuator indicated diagrammatically at 116 is provided for connecting and disconnecting the clutch. The arrangement is such that when the clutch actuator 116 is energized, the clutch is connected, causing feed conveyor 110 to be actuated.

The control band 107 is provided with actuating means 108, which are diagrammatically illustrated as upstanding portions of the band 107 but which may if desired take other convenient forms. The control elements 108 are definitely correlated to predetermined designs 120 formed in the design band and the relationship is such that when a piece of fabric is placed on the feed conveyor 110 it will remain motionless until the clutch actuator 116 is energized. A relay 121 having a toggle 122 is located in the path of the upstanding control elements 108 so that when an individual design 120 has reached a predetermined point the relay 121 will be actuated, thus energizing the clutch actuator 116, starting the feed conveyor 110 in motion. The parts are so arranged that the cover fabric, properly positioned on the feed conveyor 110 passes between the rolls 103 and 105 in timed relation to the advance of the individual design 120 so that the design may be formed on the fabric in accurately predetermined position.

By this means it is possible to place individual designs symmetrically upon individual cover fabrics, as will readily be appreciated.

Instead of providing a separate control band 101, it will be appreciated that the design band 106 may have suitable relay actuating means thereon for controlling the clutch actuator.

Preferably feed conveyor 110 is associated with a table having marks thereon indicating the proper positioning of the individual fabric so that upon advance of the conveyor belt 110 the fabric will be advanced in accurately timed relation to the advance of the design element 120.

In Figure 9 we have illustrated a somewhat different form of design band 130 comprising individual links 131 pivoted together as indicated at 132. These links may conveniently be made of metal, and as indicated in Figure 9 they present a flat bottom surface in contact with the fabric advanced through the machine. Any suitable design may be engraved thereon. For purposes of illustration, the design indicated at 120 in Figure 8 may be engraved thereon, and of course may extend over a plurality of separate links.

If this type of design band is provided, preferably the feed roll 133, corresponding to the feed roll 105 in Figure 7, is a polygon having sides equal in length to the effective length of the individual links 131. As indicated in Figure 10, the individual links 131 are provided with recesses 134, constituting a design, and, if desired, these recesses may extend completely through the link to avoid entrapment of air therein. We have indicated at 135 an opening through the top of the recess 134 to permit the escape of entrapped air. In Figure 11 we have illustrated a plurality of links 131 having a portion of the design 120 formed therein. As indicated in these figures, the design extends across the plurality of links.

While we prefer to provide the apparatus as previously described, with the heating element located at the rubber side of the composite side of the fabric, it will be appreciated that this arrangement need not be followed, and, if preferred, heat may be transferred from the design band through the fabric to the rubber. This of course requires the use of temperatures at a low enough level to avoid injury to the cloth.

While we have illustrated and described several specific embodiments of our invention, it will be apparent to those skilled in the art that various additions, modifications, omissions, com-

bination and substitutions may be made which will be within the spirit and scope of our invention as defined by the appended claims.

What we claim as our invention is:

1. Apparatus of the character described comprising an elongated heating element, pressure means resiliently urged toward said element, a pair of endless bands movable together between said element and pressure means, a feed conveyor belt arranged to advance separate sheets of material to be embossed between said bands, one of said bands having design recesses therein, drive means for said feed conveyor belt and for said bands, and means automatically operable in accordance with the advance of said design recesses for intermittently driving said conveyor belt to advance material in properly registering relation to said design recesses.

20 2. Apparatus of the character described comprising an elongated heating element, pressure means resiliently urged toward said element, a pair of endless bands movable together between said element and pressure means, a feed conveyor belt arranged to advance sheet material to be embossed between said bands, one of said bands having design recesses therein, drive means for said feed conveyor belt and for said bands, and means for intermittently driving said conveyor belt to advance material in properly registering relation to said design recesses, said last means comprising conveyor control elements movable with said band having design recesses therein, and a clutch for controlling the driving 30 of said conveyor belt controlled by said control elements.

3. Apparatus of the character described comprising an elongated heating element, pressure means resiliently urged toward said element, a pair of endless bands movable together between said element and pressure means, a feed conveyor belt arranged to advance sheet material to be embossed between said bands, one of said bands having design recesses therein, drive means for said feed conveyor belt and for said bands, and means for intermittently connecting said drive means to said conveyor belt to advance material in properly registering relation to said design recesses, said last means comprising conveyor control elements movable with said band having design recesses therein.

WINFIELD L. WEBSTER.
ELBURN J. RANN.
